Attorney

UNITED STATES PATENT OFFICE.

MILTON F. WILLIAMS, OF ST. LOUIS, MISSOURI, ASSIGNOR TO WILLIAMS PATENT CRUSHER & PULVERIZER CO., OF ST. LOUIS, MISSOURI, A CORPORATION OF MISSOURI.

SLIDING BASE FOR GRINDERS.

1,350,691.

Specification of Letters Patent. Patented Aug. 24, 1920.

Application filed May 12, 1919. Serial No. 296,584.

To all whom it may concern:

Be it known that I, MILTON F. WILLIAMS, a citizen of the United States, residing at St. Louis, State of Missouri, have invented 5 certain new and useful Improvements in Sliding Bases for Grinders, of which the following is a specification.

This invention relates to certain new and useful improvements in sliding bases for 10 grinders, the peculiarities of which will be hereinafter described and claimed.

The object of this invention is to provide 15 a grinder having air connections with the stationary discharge pan below the grinder, with a slidable base for the grinder and a telescopic connection with the air pipes.

In the accompanying drawing on which 20 like reference letters indicate corresponding parts Figure 1 represents a plan view of a grinder and a base illustrating my invention; Fig. 2 a sectional elevation across the shaft of the grinder along the line 2—2 of Fig. 1; and Fig. 3 a sectional elevation of the base on the line 3—3 of Fig. 1.

The letters A—A designate timber sills forming the sides of a rectangular frame, the ends B—B connecting said sills being of 25 lesser depth than the sills A to provide a space below the cross beams B and between the ends of the sills A. At one end of the sills the space mentioned is filled by a header C provided with a regulating air valve D for admitting air between the sills. The other end of the sills is provided with 30 a header E having a pipe F connecting it to an exhaust fan G on the shaft of the grinder or elsewhere. The sills A are grooved out at their inner opposing faces, and in the grooves are mounted the side 35 pieces H—H of a rectangular frame formed by said side pieces H and cross bars I. This frame forms a slidable base for the grinder J secured to said base by bolts K as shown in Fig. 1. In Figs. 2 and 3 it is shown that 40 these bolts K extend down through the sliding base and the side sills A, in which sills are provided elongated openings or slots L to provide for the sliding movement of the base. On the under side of the sills A at the 45 said bolts K, are recess washers M as shown in Fig. 3 for engagement of the head of the bolts after the sliding base is adjusted and the bolts are tightened to hold the sliding base and sills firmly together in the desired position. Below the cross bars H of

the sliding base are plates N and O preferably secured to said cross bars and extending outward in both directions toward the cross beams B over the headers C and E, and forming a slip joint practically air 60 tight with said headers.

The grinder with its sliding base is adjustable upon the sills A—A by means of rod P passing through one of the cross beams B, and a nut Q secured to the outside 65 of said cross beam. The other end of the rod is connected to the sliding base so that by turning the nut upon the threaded end of the rod P, said base is slidably adjusted. The tightening of the belt R on the driving 70 pulley S of the grinder is thus readily effected, and the plates N and O, by means of their telescopic connection with their respective headers maintain a practically air tight connection with a stationary pan T below 75 the grinder and connecting the headers C and E.

The side pieces H of the sliding base and also the top of the sills A, are grooved to receive a bearing strip U that is practically 80 flush or even with the top of the sill and the sliding frame at each side, and extends from end to end of the sill A as shown in Fig. 1. These bearing strips hold down the sliding frame within the sills A—A against 85 outward tendency due to the pull of the driving belt. When the bolts K are tightened after the adjustment of the belt to the proper tightness, the sliding base and the sills are firmly fastened together by said 90 bolts K which pass through the bottom flange of the grinder, and thus clamp the grinder firmly down upon the bearing strips U at each side. Anchor bolts V pass down through the bearing strips U at each end 95 and through the sills, and secure the mill and its base to the floor or foundation, and thus form a rigid construction and prevent any tendency to chatter or shake that may occur through looseness of the joints and 100 connections.

Additional bolts may also be used if desired.

It will be seen that the tightening of the driving belt R may be readily effected by 105 adjusting the grinder and its sliding base upon the sills, and at the same time maintain the air tight connection between said sliding frame and the air inlet and discharge pipes at each end of the pan T, so 110

that the delivery of the material discharged from the grinder into the pan T may be readily effected, and without interfering with the adjustment of the driving belt as above described.

5 A slip joint W in the pipe F allows for the movement of the fan when it is moved with the machine as in this case, but is not required when the fan is independent.

10 The closing plates N and O are bent over at the sides of the pan T, as indicated in Fig. 3 to improve the sliding joint connection of the plates with the top edges of the pan. The ends of the stationary pan make 15 tight engagement with the headers respectively.

New belts whether of canvas or leather always stretch so much that they require taking up and shortening in order to keep 20 them tight and operative. In other machines besides grinders a sliding base is often provided for quickly taking up the slack in a belt, but in grinders the movement varies the relative position of the discharge opening with regard to the stationary pan or receptacle below the grinder which is provided with air connections,— 25 that is, pipes connecting said pan with an exhaust fan and other pipes supplying the air to the opposite end of the pan, whereby 30 the discharge of material delivered to the pan is effected as in the case shown. The discharge opening through the sliding frame will be moved to another position 35 above the open-topped pan as the slack is taken up, and in any adjusted position the balance of the opening of the pan must be kept closed. It is now evident that my 40 plates N and O making close connection with the top at each end of the pan T and secured to the sliding base or frame, will move with the frame and close the balance of the top of the said pan that is not required by the discharge opening in the 45 frame, whatever the adjusted position of said frame.

While I have shown a telescoping pipe joint W for the pipe F leading to the fly-wheel fan it is evident that if the fan be an 50 independent fan and not movable with the grinder this pipe joint W is not required.

The air inlet pipe E may be connected to the usual return air pipe, or may be an independent air inlet for the outside air as 55 shown in the drawing.

I claim:

1. A device of the character described, comprising parallel stationary side sills separated to afford a space between them and securely anchored, a stationary pan open 60 at the top and located in said space and having inlet and outlet connections, a slideable frame to support a grinder and mounted on said side sills above said pan, a grinder on said frame adapted to discharge into said pan, means to slide said frame and grinder carried thereon, and a closing plate located above the top of the said pan at each end and secured to and movable with the sliding frame forming slip joints for closing the 70 top of said pan at each end of the frame, substantially as described.

2. A device of the character described comprising a pair of stationary separated side sills grooved on their inner faces, a 75 slideable frame mounted in said grooves and having a discharge opening, a grinder on said frame adapted to discharge through said opening in the frame, means to slide said frame and grinder, bolts passing vertically through said frame and through slotted holes in said sills and through the flange of the grinder for securing the sliding frame and grinder firmly in any adjusted position, a pan located between said 85 sills below the discharge opening in the sliding frame, and means to cover the balance of the top of said pan outside the discharge opening of said frame.

3. A device of the character described 90 comprising a pair of parallel separated stationary side sills grooved at their inner faces, a slideable frame mounted in said grooves and having a discharge opening, a grinder on said frame adapted to discharge 95 through the said opening, a bearing strip on top of each side sill and extending laterally over the sliding frame to hold it down in said groove, anchor bolts passing through said strips and side sills, a stationary pan 100 located between said sills and below the discharge opening of said sliding frame, means to close the top of said pan except at the said discharge opening, and means to secure the side sills, the sliding frame, and the 105 grinder firmly together in any adjusted position.

In testimony whereof I have affixed my signature.

MILTON F. WILLIAMS.
